US00D519394S

(12) **United States Design Patent** (10) **Patent No.:** **US D519,394 S**
DiPasquale (45) **Date of Patent:** **** Apr. 25, 2006**

(54) **DOOR/WINDOW SENSOR**

(75) Inventor: **Kathy E. DiPasquale**, Baltimore, MD (US)

(73) Assignee: **Black & Decker, Inc.**, Newark, DE (US)

(**) Term: **14 Years**

(21) Appl. No.: **29/216,969**

(22) Filed: **Nov. 10, 2004**

(51) **LOC (8) Cl.** **10-05**

(52) **U.S. Cl.** **D10/106**

(58) **Field of Classification Search** **D10/121, D10/106; D13/165; D14/346, 341; D26/85, D26/51, 26; 250/221; 340/555, 556**

CLAIM

The ornamental design for a door/window sensor, as shown and described.

DESCRIPTION

FIG. 1 is a perspective view of a door/window sensor in accordance with the present invention;

FIG. 2 is a front plan view of the door/window sensor of FIG. 1;

FIG. 3 is a bottom plan view of the door/window sensor of FIG. 1;

FIG. 4 is a left side plan view of the door/window sensor of FIG. 1;

FIG. 5 is a rear plan view of the door/window sensor of FIG. 1;

FIG. 6 is a top plan view of the door/window sensor of FIG. 1; and,

FIG. 7 is a right side plan view of the door/window sensor of FIG. 1.
